[57] CLAIM

The ornamental design for a bowling shoe protector, substantially as shown.

DESCRIPTION

FIG. 1 is a perspective view taken from the top, front and left side of a bowling shoe protector, showing my new design;

FIG. 2 is a left side elevational view thereof, the right side being substantially a mirror image thereto;

FIG. 3 is a top plan view thereof;

FIG. 4 is a front elevational view thereof;

FIG. 5 is a rear elevational view thereof; and,

FIG. 6 is a bottom plan view thereof.
